UNITED STATES PATENT OFFICE.

GEORGE E. HEIDBREDER, OF QUINCY, ILLINOIS.

COMBINED COAL AND GAS RANGE.

1,156,999.

Specification of Letters Patent. Patented Oct. 19, 1915.

Application filed July 20, 1915. Serial No. 40,913.

To all whom it may concern:

Be it known that I, GEORGE E. HEIDBREDER, a citizen of the United States, residing at Quincy, in the county of Adams and State 5 of Illinois, have invented a new and useful Combined Coal and Gas Range; and I do hereby declare the following to be a full, clear, and exact description of the invention, such as will enable others skilled in the 10 art to which it appertains to make and use the same.

This invention relates to a combined coal and gas range, and one of the objects of the invention is to improve the combined coal 15 and gas range set forth in George E. Heidbreder's application for patent filed March 20, 1915, Serial No. 15,728.

Another object of the invention is to provide a heating space or passage upon one 20 end, the bottom and the rear wall of the oven.

Another object of the invention is to provide a gas heating space on the lower part of the other end wall and the lower part of 25 the rear wall of the oven, and in which case to provide a gas burner, there being openings in the gas heating space into the oven.

Another object of the invention is to provide sliding dampers for the gas heating 30 space, one at the rear of the stove or range, the other at the bottom of the gas heating chamber or space at one end of the oven, and a damper for controlling an opening of communication between the oven and the 35 passage at one end of the oven.

Another object of the invention is the provision of a valve, the valve stem of which 40 has means of connection with the slide dampers of the gas heating space and the damper which controls the opening of communication between the oven and said passage, whereby the gas may be turned on and the damper simultaneously opened.

Another object of the invention is the 45 provision of a damper which may be opened so as to carry the products of combustion from the fire box of the range direct through the flue at the rear of the range. The closing of this damper, after the fire in the box 50 is thoroughly burning causes the products of combustion to pass through the passage over the top of the oven and through the passage of one end of the oven, then through the passage under the oven, making a loop, 55 then returning to another passage at the end of the oven, and finally passing out

through the passage at the rear of the oven and through the outlet flue.

In practical fields the details of construction may necessitate alterations, falling 60 within the scope of what is claimed.

The invention comprises further features and combinations of parts, as hereinafter set forth, shown in the drawings and 65 claimed.

In the drawings:—Figure 1 is a front elevation of the improved combined coal and gas range constructed in accordance with the invention, Fig. 2 is a plan view of the range, showing parts broken away, to better 70 illustrate a damper for controlling the products of combustion in the fire box to the outlet flue. Fig. 3 is a sectional view on line 3—3 of Fig. 2. Fig. 4 is a rear elevation of the range. Fig. 5 is a horizontal sectional 75 view on line 5—5 of Fig. 4. Fig. 6 is a vertical sectional view on line 6—6 of Fig. 5. Fig. 7 is a diagrammatic view illustrating a burner, the valve thereof, the slide damper at the rear gas heating space and 80 the damper at the side gas heating space, and the means for simultaneously operating the valve and said damper, and the damper which controls the opening of communication between the oven and the passage at 85 one end thereof.

Referring to the drawings, more especially, 1 designates the casing of the range, which may be any suitable shape or configuration, and is provided with a fire box 2 and ash pit 3 and the oven 4. A passage *c* extends across the top of the oven and merges into a passage *d* between one end wall of the oven and the end wall of the range, which passage *d* extends angularly and merges into a passage *e* between the bottom of the oven and the bottom of the range. This passage *e* makes a loop *g* and merges into the passage *h*, which in turn merges into an angularly arranged passage *k* extending upwardly between one end wall of the oven and the adjacent end wall of the casing of the range and communicates with the passage *m*, which in turn merges into the outlet flue as shown at *n*. The wall *p* divides the top of the range so as to form the passage *c* and the space *s* for the burners *a'*, *b'* and *c'*, there being an additional space *a²* in the top of the range for the burners *a³* and *a⁴*, all of which burners receive their supply of gas through the pipe *a⁵*. A slide damper *a⁶* is provided controlling 100 105 110

the opening a^7 , so as to permit air to enter the space or passage c , where it merges into the first angularly arranged passage. The damper a^6 has a slot a^8 , through which a headed lug extends shown at a^9 to guide the damper. The rod a^{10} is connected to the damper whereby the same may be operated. The rear wall b^2 of the passage c has an opening b^3 . A damper b^4 is mounted in guides b^5 for controlling the opening b^3 . A rod b^6 is connected to the damper b^4 as shown at b^7 for adjusting the damper. This rod has a right angled upwardly extending part b^8 slideable in the slot b^9 in the top of the range to guide the rod as it is manipulated. The damper b^4 is provided for the purpose of permitting the products of combustion (when a fire is first made in the fire box, or to give the fire a quick draft to cause it to burn) to pass directly out through the outlet flue. The outlet flue is designed to be connected at g^a to the range. The lower portion of the rear wall of the oven, and the end wall 7 of the oven at its lower portion has a gas burner heated space angular as shown, which comprises the spaces 11 and 12 in communication as shown at 13 . The bottom 14 of the range adjacent the space 11 is provided with elongated triangular shaped openings 15 , with which the pivoted damper 16 cooperates, for controlling the fresh air draft into the space 11 of said passage, so that the burner 17 will have a proper combustion. The burner 17 consists of a perforated tube or pipe 18 extending through the space 11 of said angular space, and through the space 12 and terminates exteriorly of the range casing into the usual air cup 19 , beyond which a suitable valve 20 is provided, and beyond the valve a pipe 21 may be connected to the source of gas supply (not shown). The rear wall of the oven and the end wall thereof adjacent the space 11 are provided with apertures 24 and 25 of communication between the oven and the spaces 11 and 12 , so that the heat from the gas burner heated spaces will enter the oven. In lighting the burner, a lighted match may be held adjacent the apertures 24 and 25 of the oven wall, after turning on the gas. The bottom of the space 12 has perforations 26 , and adjacent this bottom is an angular slide damper 27 , which is provided with perforations or openings 28 , through which, when in registration with the perforations or openings 26 air is drawn into the space 12 , in order to create the proper combustion when the burner is lighted. The greater portion of the angular slide damper is guided by the elongated slots 30 and pins 31 . The end 32 of the slide damper 27 has a notch and angle end connection 33 with the pivoted damper 16 , so that when the damper 27 is operated, so as to throw the apertures

or openings 28 of the damper in and out of registration with the openings or apertures 26 , the pivoted damper is oscillated, to uncover or cover the openings 15 in order to control the intake of air into the spaces 11 and 12 , in order to control the combustion of the burner. Mounted in bearings 34 of one corner of the range is a vertical shaft 35 having an arm 36 secured to it as at 37 . This arm 36 has an eye 38 , which receives the angled end 39 of the rod 40 , which is guided in the wall of the range, as at 41 and has its end 42 connected at 43 to the damper 44 , so that when the shaft 35 is rocked in one direction or the other, the damper 44 (which covers the opening 45) is opened or closed. When opening the damper 44 additional heat is allowed to pass from the oven into the passage d to maintain the proper temperature in the oven. The valve 20 has a valve arm 46 extending laterally, and which arm enters the eye 47 in the end of the angular arm 48 of the vertical shaft 35 . An additional arm 49 is fixed to the shaft 35 and has a downwardly extending portion 50 engaging a transverse slot 51 in an extension 52 of the slide damper 27 .

Upon referring to Figs. 5 and 7 of the drawings it will be observed that by rocking the shaft 35 in the direction of the arrow a the damper 44 and the valve 20 will be opened, and the slide damper operated in order to throw its apertures or openings 28 into registration with the openings or apertures 26 . At the same time the slide damper 27 is so operated, the pivoted damper 16 will be oscillated to uncover the openings 15 , in order to permit the burner to receive a proper supply of oxygen, whereas the damper 44 is opened to permit of greater supply of heat to enter the oven. A reverse movement of the shaft 35 will close the dampers 44 , 27 and 16 , and also close the valve 20 .

To light the gas burner a lighted match or the like may be dropped down through the tube m^2 , which is funnel shaped at its lower end, as shown at m^3 particularly in Fig. 4. After the gas is turned on the match or the like is dropped into the tube, thereby igniting the gas in the chamber or space 12 and space 11 .

The invention having been set forth, what is claimed as new and useful is:—

1. In a range, the combination of casing having an oven having an angular space adjacent the lower rear wall and the lower part of one of the end walls constituting a heating space, a gas burner tube in said space and provided with a valve, and apertures of communication between the space and the lower part of the oven, and means for opening and closing the valve.

2. In a range, the combination of casing having an oven having an angular space adjacent the lower rear wall and the lower part

- of one of the end walls constituting a heating space, a gas burner tube in said space and provided with a valve, and apertures of communication between the space and the 5 lower part of the oven, and means for opening and closing the valve, the lower wall of the space at the rear of the oven having openings, a slide damper controlling said openings and having connections with the 10 operating means of the valve, whereby the slide damper may be opened or closed as the valve is operated.
3. In a range, the combination of casing having an oven having an angular space adjacent the lower rear wall and the lower part 15 of one of the end walls constituting a heating space, a gas burner tube in said space and provided with a valve, and apertures of communication between the space and the 20 lower part of the oven, and means for opening and closing the valve, the lower wall of the space at the rear of the oven having openings, a slide damper controlling said 25 openings and having connections with the operating means of the valve, whereby the slide damper may be opened or closed as the valve is operated, the bottom of the space at the end wall of the oven having triangular shaped openings, an oscillatory damper for controlling said triangular openings, said oscillatory damper having a notch and angular end connections with the slide damper to be operated simultaneously with the slide damper and the operation of the valve.
- 35 4. In a range, the combination of casing having an oven having an angular space adjacent the lower rear wall and the lower part 40 of one of the end walls constituting a heating space, a gas burner tube in said space and provided with a valve, and apertures of communication between the space and the lower part of the oven, and means for opening and closing the valve, the lower wall of the space at the rear of the oven having 45 openings, a slide damper controlling said openings and having connections with the operating means of the valve, whereby the slide damper may be opened or closed as the valve is operated, a flue or passage adjacent one end wall of the oven having communication with the outlet flue of the range and an opening of communication with the oven, a pivoted damper to control the opening of communication between the oven and the flue and provided with a connection with the valve operating means so that the pivoted damper may be opened or closed at the same time the valve is operated and simultaneously with the oscillatory and slide dampers.

In testimony whereof I have signed my name to this specification in the presence of two subscribing witnesses.
